UNITED STATES PATENT OFFICE

ERIC P. MUNTZ, OF BUFFALO, NEW YORK

BUILDING

Application filed December 30, 1927. Serial No. 243,591.

This invention relates to a building and more particularly to a construction of a system of ramps for a building which when so equipped is particularly adapted for the storage of automobiles and other vehicles on the different floors thereof, the ramps permitting the automobiles to be driven from one floor to another.

Heretofore garages employing ramps have been specially designed to provide different "levels" the level on one side of the garage being substantially half way between the levels on the other side of the garage and half ramps were employed between the staggered levels, two ramps being necessarily traversed to elevate the car from one floor to the floor above. With this construction, it is necessary to provide a specially designed building which is usable for storage garage purposes only, and should the character of the neighborhood change or any other conditions render the running of a large storage garage unprofitable, the building is wholly unfitted for any other use and can only be readapted to new requirements at great expense. Financial institutions have therefore been unwilling to finance garages of this character as the lack of ready convertibility of the building to meet new conditions makes an investment of this character highly speculative.

Moreover, with such a building there is necessarily an extra half floor at the bottom of the building and an extra half floor at the top which necessarily results in a less economical building in point of storage space, and a more expensive building to construct.

Also with the increased number of short ramps a greater number of right angle turns are necessary to drive the car from different levels which makes such a system of ramps considerably more cumbersome to use than if a system of single ramps were employed between the floors.

The principal object of the present invention is to provide a system of ramps for use in a building of standard construction in which the floors are all on the same level and should it become desirable to change the use of the building, say to a department store, factory, office building, apartment house or the like,

the system of ramps can be removed easily and with small expense. The ramp embodying the present invention can also readily be installed in buildings now used for such other purposes.

A further object is to provide such a ramp which can be removed without interfering with the building proper either by cutting or changing any structural part of the building.

Another aim is to produce a ramp system, the structural parts of which upon removing the ramps can be used to completely fill the ramp openings in the floors without substantial alteration, thereby effecting a substantial saving in converting the building.

A still further object is to provide such a system of removable ramps which are so placed as to occupy the least floor area and provide the maximum amount of uninterrupted floor area for a given space and also to so arrange the driveways on the several floors as to leave the maximum available storage space.

Another aim is to design a system of removable ramps which permits economical construction of the building and eliminates irregularity in the arrangement of columns or general design of the building.

Another object is to arrange the ramp openings so as to form a vertical shaft or well so that, upon removing the ramps, the shaft is, if desired, available as a light, ventilation or elevator shaft.

In the accompanying drawings:

Figure 1 is a floor plan of a building of standard construction equipped with my system of ramps. Figure 2 is a section through the building showing the general arrangement of the system of ramps. Figure 3 is a fragmentary top plan view of one of the series of up and down ramps. Figure 4 is a vertical longitudinal section through one of the ramps. Figure 5 is a vertical transverse section taken on line 5—5, Fig. 4. Figure 6 is a fragmentary transverse section through one of the curbs of the ramp. Figure 7 is a view similar to Fig. 5 but showing a modified construction.

Similar reference numerals refer to like parts in each of the several views.

In its general organization this invention comprises a building composed of a series of floors each of which is provided with an opening which openings are arranged one above the other so as to form a shaft, a supporting structure arranged in the shaft and supporting the up and down ramps which extend from one floor to the next succeeding floor, and a driveway leading from one side of the shaft to the other so that the automobiles can be driven up the ramps and around the driveways to reach the desired floor.

15 The form of building shown in Figs. 1 and 2, is made of concrete or the like and includes an exterior wall 10, exterior wall columns 11, a plurality of horizontal floors 12 which may be made of poured concrete or precast concrete slabs and interior supporting columns 13 which are suitably spaced to adequately support the floors. At one end of the building each floor is provided with an opening 14 which openings run along the wall 10 of the 25 building and are arranged in vertical alignment so as to form a vertical shaft or well which extends upwardly from the ground floor 15 and houses the ramps.

The ramps are supported on vertical columns which are suitably supported at their lower ends at the bottom of the shaft and extend substantially the full height thereof as indicated in Fig. 2. These columns are arranged in rows extending lengthwise of the 35 openings, the columns 16 of one row being arranged along the sides of the openings 14, and a row of columns 17 being arranged along the center of the shaft.

The ramps are arranged in two series, the 40 series of down ramps being supported between the rows of columns 16 and 17 and the series of up ramps being arranged between the central row of columns 17 and the exterior columns 11 of the building, these 45 columns 11 being provided with ledges 18 for the support of the ramps. As best indicated in Figs. 3 and 4, each ramp comprises a transverse supporting beam 19, a pair of longitudinal channel beams 20 secured at 50 their ends to the cross beams 19 and extending along the sides of the ramp, a pair of longitudinal central I-beams 21 secured to the cross beams 19 and a floor composed of planks or precast concrete slabs 22 which rest 55 on the upper side of this steel structure.

The ends of the cross beams 19 of the down ramp are secured to the sides of the columns 16 and 17 of the inner and central rows of columns, and the cross beams 19 of the up 60 ramps are secured at one end to the central columns 17 and at their other ends rest on the ledges 18 formed on the building columns 11. Any usual and well known method may be employed for securing the beams together, 65 the beams being shown in the drawings as tied

together with angle plates which are riveted to both members.

Each ramp extends from the end of one opening to the opposite end of the opening on the next succeeding floor. To support the ends of the ramp, angle bars 23 are bolted at the opposite ends of the openings 14 and the longitudinal bars 20 and 21 at the ends of each ramp rest on the shelf formed thereby as best shown in Fig. 4. In order to prevent the automobile on the ramp from striking the columns at opposite sides thereof and injuring the car or the structure, a protective curb is provided. This curb as best shown in Fig. 6 comprises a plurality of bars 24 which are securely riveted to the outer faces of the longitudinal channel bars 20 and extend upwardly through openings provided in the concrete slabs forming the ramp flooring. To the inner sides of these bars are secured a plurality of wooden bars 25 which form a wall along the sides of the ramp. The bars 24 are preferably bent outwardly to form an inclined wall and is further protected by a wooden rail 26 at its base.

Fig. 1 illustrates a floor plan which is suitable for use in connection with the present invention. In this plan two driveways 125, 126 terminate at the opposite ends of the ramp and extend transversely thereof the full length of the room. These two driveways are connected by a central driveway 127 at the center of the floor and a central driveway 128 crosses this last driveway. By this means the automobiles driven up the ramp pass from the up ramp leading to this floor onto the driveway 125, and through the driveways 127 and 126 onto the up ramp at the other end of the shaft which carries them up to the next succeeding floor. By this means the floor area within the main drive, i. e., that area bounded by the shaft and the driveways 125, 126 and 127 may be fully utilized for storage purposes as indicated in Fig. 1.

It is obvious that the ramp system and shaft may be placed in the center of the building with equal facility should this be found more desirable. This position of the shaft is indicated by the dotted line 28 in Fig. 1.

In the modified form of the invention shown in Fig. 7, the ramp system is constructed wholly independently of the building structure. In this form, three rows of columns 29, 30 and 31 are placed along the opposite sides and center of the shaft and the columns 29, 31 of the outer rows are connected by inclined I-beams 32, and the central row of columns 30 are connected by two series of channel bars 33, these I-beams 32 and channel bars 33 forming the side supporting bars of the ramp. The precast concrete slabs or planks 34 are laid upon the upper flanges of these I-beams and channel bars and are held in place by a channel rail 35 which also supports the lower end of a

wooden guard board 36. The upper end of this guard plate is preferably secured to an angle plate 37 on the columns and at its lower end this guard plate is secured to a wooden 5 filler bar 38 in the channel rail 35. In addition to forming a completely independent structure this form is considerably less expensive to construct and provides a greater head room between the ramps by reason of the elimination of all cross beams in the ramp structure, which increase in head room is an important factor since the distance between ramps is necessarily less than the head room provided between the floors of the building, 10 and it is furthermore desirable to have overhead sprinkler systems on the ramp to guard against the danger of fire.

Should it be desirable to remove the ramp system and use the shaft as a light shaft this 20 is accomplished by removing the ramp system, this being readily done since it is independent of the building structure. If it is desired to substitute elevators for the ramp in converting the building, for example, into 25 an office building, the shaft is of proper proportions to receive an elevator system. If, on the other hand, it is desired to remove the ramp and fill the openings in the floors so as to use the full area thereof, the ramps are 30 first dismantled, the longitudinal beams cut to fit between the columns in a horizontal position and each ramp is then reassembled so as to fill the opening in the floor, the curbing being, of course, omitted. It will be 35 noted, as best shown in Fig. 3, that the concrete slabs or planks extend substantially half the width of the shaft so that upon bringing the ramps to horizontal positions to fill the openings in the floor, the two series 40 of concrete slabs completely fill the opening.

As a whole this invention provides a system of ramps which permits the use of the maximum floor area for storage, it is adapted 45 to be used in buildings of regular construction and having regular floors, it is easily removable and its parts can readily be used in filling the ramp openings in the floor should it become desirable to use the building 50 for other purposes. It is built independently of the building structure and necessitates no alteration of the building structure in removing it.

I claim as my invention:

55 1. A building including a series of spaced horizontal floors each of which has an opening provided therein, said openings being arranged in vertical alinement and forming a vertical shaft and a ramp structure arranged in said shaft, said ramp structure including parallel rows of metal columns arranged in said shaft and mainly supported at their bases, and a plurality of fabricated inclined ramps 60 removably secured to said columns between said rows and mainly supported there-

by, said ramps removably abutting the said floors adjacent the ends of said openings whereby a continuous system of ramps is provided between the several floors, and the ramp structure is substantially independent of the building and said ramps consisting of two series, the ramps of each series being parallel with one another and arranged at an angle to the ramps of the other series. 70

2. A building including a series of spaced horizontal floors each of which has an opening provided therein, said openings being arranged in vertical alinement and forming a vertical shaft and a ramp structure arranged in said shaft, said ramp structure including parallel rows of metal columns arranged in said shaft and mainly supported at their bases, and a plurality of fabricated inclined ramps removably secured to said columns between said rows and mainly supported thereby, said ramps including inclined metal beams extending along each row of columns and mainly supported thereby, transverse horizontal beams connecting the inclined beams, additional inclined beams connecting the several transverse beams, transverse floor members carried by said beams, and each of said ramps including curbs consisting of supporting members secured to and projecting upwardly from some of said inclined beams and rails carried by said supporting members, said ramps removably abutting the said floors adjacent the ends of said openings whereby a continuous system of ramps is provided between the several floors and the beams and floor members of said ramps being each of sufficient length to permit their use in filling said openings upon removing said ramp structure. 80

In testimony whereof I affix my signature. 105
